(57) **CLAIM**

The ornamental design for a USB memory device, as shown and described.

DESCRIPTION

FIG. 1 is a top front right perspective view of the USB memory device.

FIG. 2 is a top plan view of the USB memory device.

FIG. 3 is a front elevational view of the USB memory device.

FIG. 4 is a right side elevational view of the USB memory device.

FIG. 5 is a right side elevational view of the USB memory device where the tab on the right has been slid so the USB connector extends out the front.

FIG. 6 is a top plan view of the USB memory device where the USB connector extends out the front; and,

FIG. 7 is a top front right perspective view of the USB memory device where the USB connector extends out the front.
